(57) CLAIM

The ornamental design for a golf bag top, as shown and described.

DESCRIPTION

FIG. 1 is a perspective view of the golf bag top;
FIG. 2 is a left side view of the golf bag top; the right side view is a mirror image of FIG. 2;
FIG. 3 is a top plan view of the golf bag top;
FIG. 4 is a rear elevational view of the golf bag top; and,
FIG. 5 is a front elevational view of the golf bag top.
The broken line showing of environment in the drawings is for illustrative purposes only and forms no part of the claimed design.
